UNITED STATES PATENT OFFICE.

CHARLES M. THEBERATH, OF NEWARK, NEW JERSEY.

IMPROVED MODE OF COVERING HARNESS-TRIMMINGS.

Specification forming part of Letters Patent No. **99,032**, dated January 18, 1870.

To all whom it may concern:

Be it known that I, CHARLES M. THEBERATH, of Newark, in the county of Essex and State of New Jersey, have invented certain new and useful Improvements in the Covering of Harness-Trimmings; and I do hereby declare that the following is a full, clear, and exact description thereof, reference being had to the accompanying drawings, and to the letters of reference marked thereon, which form a part of this specification.

The nature of my invention consists in a new mode of covering harness-trimmings, whereby the rapid wear and destruction thereof are obviated.

In order to enable others skilled in the art to which my invention appertains to make and use the same, I will now proceed to describe the manner in which the same is or may be performed, referring to the annexed drawings, in which—

Figure 1 is a perspective view, and Fig. 2 a side view, of a turret-ring covered with leather in my new and improved way.

The usual manner of covering such or other articles has been to make a seam in the center, which leaves a ridge more exposed to wear than the balance of the covering. This soon wears, so that the thread breaks and the seam opens, and, as a general thing, the entire cov-

ering is spoiled and must be replaced. To obviate this, I make two seams—one at or near each edge—which leaves the center smooth and even, so that one part cannot wear out sooner than any other.

In the drawings, A represents the usual metallic ring, having a screw, B, to fasten it into the saddle in the usual way. The ring A is covered with a leather or other covering, C, having a seam near or at each edge, leaving almost the entire outer surface smooth and even. The covering C may be made of any material, whether elastic or non-elastic, and may be applied to any and every kind of harness-trimmings in precisely the same manner. Rubber may be used for such trimmings.

Having thus fully described my invention, what I claim as new, and desire to secure by Letters Patent, is—

The method herein described of covering harness-trimmings with a seam at or near each edge, substantially as and for the purposes herein set forth.

In testimony that I claim the foregoing as my own I affix my signature in presence of two witnesses.

CHAS. M. THEBERATH.
